UNITED STATES PATENT OFFICE

DAVID W. SCOBIE, OF CAMBRIDGE, WISCONSIN.

BOB-SLEIGH.

SPECIFICATION forming part of Letters Patent No. 402,983, dated May 7, 1889.

Application filed February 26, 1889. Serial No. 301,221. (No model.)

To all whom it may concern:

Be it known that I, DAVID W. SCOBIE, of Cambridge, in the county of Dane and State of Wisconsin, have invented new and useful Improvements in Bob-Sleighs; and I do hereby declare the following to be a full, clear, and exact description of said invention, reference being had to the accompanying drawings, and to the letters of reference marked thereon, which form a part of this specification.

My invention relates to improvements in bob-sleighs; and it pertains to the peculiar construction and arrangement of the knees and cross-beams which communicate between the runners of the respective bobs, whereby either one or both of the runners of the respective bobs are free to oscillate upward and downward, either together or separately, beneath the cross-beams without turning or twisting said cross-beams.

The construction of my improvements is explained by reference to the accompanying drawings, in which—

Figure 1 represents a perspective view of a bob-sleigh in which such improvements are embodied. Fig. 2 represents a side view provided with my improved knee and cross-beam, shown part in section. Fig. 3 represents a vertical section through the knee and cross-beam, drawn on line X X of Fig. 2. Fig. 4 represents a bottom view of my improvement, part in section, drawn on line Y Y of Fig. 2.

Like parts are represented by the same reference-letters throughout the several views.

The runners A, bolsters B, and reach C are all constructed in the ordinary manner.

The improvements to which my invention relates pertain to the peculiar construction and arrangement of the cross-beams D D and the knees E. The knees E are preferably formed of metal, the lower ends of which are formed in two parts or arms, a a, which diverge from each other toward the right and left beneath the beams, and are secured at their lower ends to the runners F by retaining bolts or rivets b b and c c. The upper ends of the knees are made concave, forming a semicircular seat, G, for the reception of the rounded or cylindrical-shaped ends H of the cross-beams D, which nicely fit in said seats

G and permit of the turning movement of the knees E beneath them as the runners oscillate upward and downward in conformity to the surface over which they are being drawn. The central portions of the seats G are provided with elongated slots I I for the reception of the lower end of the beam-retaining bolts J J. The bolts J J are rigidly secured within apertures provided therefor in the ends of the cross-beams D, while the lower ends extend down through the seat G and are provided with retaining-nuts K.

L is a bearing-plate interposed between the convex surface of the cross-beam D and the heads of the beam-retaining bolts J. The retaining-nuts K are left sufficiently loose to permit of the free oscillating movement of the runners and knees beneath the cross-beams. Thus it is obvious that when one of the runners is thrown upward in passing over an obstruction, as shown in Fig. 1, said runner is permitted to turn freely beneath the load without twisting or straining the beam connected therewith. It is also obvious that both of the runners in either bob are permitted to turn in passing over an uneven surface beneath the load without twisting the beams or straining the other parts of the sleigh connected therewith.

Having thus described my invention, what I claim as new, and desire to secure by Letters Patent, is—

1. In a bob-sleigh, the combination, with the runners of the respective bobs, of the knees E E, provided with concave bearings or seats G, for the reception of the ends of the cross-beams, and bolt-retaining slots I, for the reception of the beam-retaining bolts J, cross-beams D D, having rounded or cylindrical bearing-surfaces H at their respective ends conforming in shape to the concave surface of said knees, and beam-retaining bolts J J, rigidly affixed at their upper ends to the ends of said cross-beams and at their lower ends within the retaining-slots I of said knees, substantially as and for the purpose specified.

2. In a bob-sleigh, the combination of the knees E E, provided at their upper ends with concave bearing-surfaces for the reception of the ends of the cross-beams and at their lower ends with diverging arms a a, secured to the

runners by retaining bolts or rivets, cross-beams D D, having cylindrical bearing-surfaces conforming in shape to the bearing-surfaces of said knees, and beam-retaining bolts 5 J, rigidly secured at their upper ends in the ends of said cross-beams and operating at their lower ends within the slots I of the beam-supporting knees, all substantially as and for the purpose specified.

In testimony whereof I affix my signature in 10 presence of two witnesses.

DAVID W. SCOBIE.
